UNITED STATES PATENT OFFICE

ROBERT CHESTNUT, OF GRANTWOOD, NEW JERSEY, ASSIGNOR TO ALUMINUM SCREW MACHINE PRODUCTS COMPANY, OF EDGEWATER, NEW JERSEY, A CORPORATION OF NEW JERSEY

HAIR-CURLING DEVICE

Application filed June 27, 1932. Serial No. 619,547.

This invention relates to hair-curling devices and more particularly to devices to be employed in connection with permanent hair-waving mechanisms.

5 In the process of curling or waving hair, a plurality of strands of hair are bound together adjacent the scalp and then wound spirally on a pencil-like instrument and in this manner the hair is prepared for the necessary subsequent treatment.

10 Various devices have been devised for spirally winding hair as above described and for the most part these devices have usually included a tubular or barrel member on which the hair was spirally wound or twisted, a rotatable bifurcated tip member adapted to engage and twist the hair, and means for rotating the bifurcated tip member.

15 In these operations the tress of hair is twisted in one direction only and tightened to any desired extent. To secure this result various means, such as coil or flat springs etc., are usually suitably disposed within the hair-curling device, permitting rotation of the bifurcated tip member in one direction and preventing its rotation in the opposite direction. The devices employed for this purpose are usually complicated in construction and very often when the operator attempts to rotate them in the wrong direction, the coil springs are deformed and the device finally becomes ineffective.

20 It is an object of this invention to provide a hair-curling device of simple construction which includes manually operated means for rotating the bifurcated hair-engaging member in one direction only and means for preventing rotation in the opposite direction, said latter means being an integral portion of the tubular portion or barrel of the device upon which the hair is spirally wound.

25 Other objects, as well as novel features and advantages of this invention, will be more apparent when the following description is considered in conjunction with the accompanying drawing in which:

30 Fig. 1 represents a side elevation of the improved hair curler;

35 Fig. 2 represents a side elevation in par-

tial section, to an enlarged scale, of the improved hair curler constructed in accordance with this invention;

40 Fig. 3 represents an end view as viewed from the right of Fig. 2;

45 Fig. 4 represents a fragmentary view of a modified form of the enlarged end of the tubular body member and its associated parts;

50 Fig. 5 represents a sectional elevation taken on the line V—V of Fig. 4;

55 Fig. 6 represents a fragmentary view of another modified form of the enlarged end of the tubular body member and its associated parts;

60 Fig. 7 represents a sectional elevation taken on the line VII—VII of Fig. 6.

65 Referring to the drawing, 10 designates a tubular body member or barrel upon which the hair is spirally wound. This member is, 70 preferably, tapered longitudinally and has a bifurcated tip member 11 rotatably mounted at its smaller or reduced end. Upon the opposite end of the barrel member 10 a cap or nut 12 is rotatably mounted, said nut and 75 the aforementioned tip member 11 being tied together by means of a central shank or bolt member 13.

80 The shank 13 is threaded at both ends and engages suitable internally threaded sockets 14 and 15 in the tip member 11 and the cap 12 respectively. The bifurcated tip member 11 is provided with a spherical seat 16 which cooperates with the rounded end of the barrel member 10 to align the parts 85 and form a tight joint therebetween. The cap 12 is provided with a counterbore 17 which snugly fits over and encases a portion of the large end of the barrel 10. A set screw 18, the threads of which are cut in opposite direction to those located on the ends of the shank 13, is screwed, in a suitable internally threaded socket in the end of the cap member 12, into contact with the end of the shank 13. This construction permits simultaneous rotation of the bifurcated tip member 11 and the cap 12 and secures the various elements of the improved hair-curling device in properly adjusted assembly.

95 A spiral groove 19 is provided on the por- 100

tion of the tubular body member 10 encased within the counterbore or cavity 17 of cap 12. The depth of this groove increases, in substantially a quarter revolution, from zero to a dimension greater than the wall thickness of the tubular body member 10 and continues at this increased depth to the end of the body member. This groove constitutes, integrally with the tubular member 10, a thread-like formation, the adjacent threads or convolutions 20 of which are separated and spaced from each other. In the preferred forms of my invention the groove 19 is V-shaped and can be quite readily formed by a suitable threading tool, the thread thus produced having a root diameter less than the interior diameter of the tubular body member 10.

The convolutions 20 produced by the spiral groove 19 are preferably flat as at 21 and are of an outside diameter permitting a snug sliding fit in the counterbore 17. The direction of the spiral groove 19 is counter clockwise with respect to the direction of the threads on the ends of the shank 13, for a purpose to be hereinafter described.

In assembling the improved hair-curling device, one end of the shank 13 is threaded into the threaded socket 14 in the tip member 11. Thereafter the tubular body member 10 is placed over the shank 13, the rounded end of the longitudinally tapered tubular member 10 seating within the spherical seat 16 of the tip member. The cap member 12 is then threaded onto the opposite end of the shank 13 through the engagement of the threads on the shank with the internally threaded portion 15 of the cap 12, and the shoulder 26 of the cavity 17 is brought into contact with the free end of the convolutions 20. The set screw 18 is then screwed into the threaded end of the cap 12 into contacting relationship with the end of the shank 13, thus securing the elements of the hair-curling device in their desired adjusted position.

It will be readily observed that rotation of the cap 12 and its connected tip member 11 relative to the body member 10 will be possible in a clockwise direction, whereas any attempt to rotate said members in a counter clockwise direction will meet with restraint in view of the expanding action of the convolutions 20 into frictional engagement with the interior surface of the cavity 17 and the shoulder 26.

In the modified form of hair-curling device shown in Figs. 4 and 5 the convolutions 22, formed integral with the tubular body member 10, are provided with longitudinal grooves 23 which present ridges in contact with the interior surface of the cavity 17 of the cap member 12. In this form an additional resistance to rotation in a counter clockwise direction is provided as the ridges will tend to bite into the surface of the counter-

bore 17. The grooves 23 also provide recesses for a lubricant, if such is considered necessary, to assist rotation in a clockwise direction. Although parallel longitudinal grooves 23 are preferred, any suitable roughened surface may be used, such as that produced by a knurling operation.

In both of the above-described examples of my invention, hair-curling devices have been shown which are adapted to be operated in a right-hand or clockwise direction. It is quite manifest that these devices may be constructed for left-hand or counter clockwise operation by reversing the direction of the threads on the rod 13 and within the bifurcated tip 11 and cap 12, and at the same time reversing the direction of the convolutions 20 and 22.

Referring to Figs. 6 and 7, another modification of the improved hair-curling device is illustrated. In this form of the invention, a device is shown which is adapted to be operated in a left-hand or counter clockwise direction. The mechanism incorporated in this embodiment of the invention for restraining rotation of the cap 12 relative to the tubular body member 10 in one direction, comprises one or more grooves 26, the depth of which is greater than the wall thickness and the length of which is less than the circumference of the tubular body member. This construction provides one or more arcuate members 27 and a slot 28 cut through these members separates them from the tubular body member at one of their ends whereas their opposite ends are integrally attached to the body member.

In this form of the invention it will be observed that rotation of the cap 12 relative to the body member 10 will be permitted in a counter clockwise or left-hand direction, whereas any attempt to rotate the cap in a clockwise direction will meet with restraint in view of the expanding action of the arcuate member or members 27 into frictional engagement with the interior surface of the cavity 17. This embodiment of the invention may also be converted for clockwise or right-hand operation by merely changing the position of the slot 28 to the opposite side of the vertical center line of the mechanism, as viewed in Fig. 7, and reversing the direction of the threaded portions of the device.

In the operation of my improved hair curler, a tress of hair, having been carefully prepared and bound with a piece of string, is secured to the tip member 11 by inserting the string within the slot 24 and tying the same in the annular groove 25. In the devices shown in Figs. 2 and 4 the nut 12 is then rotated in a clockwise direction, which action rotates the bifurcated tip member 11 to spirally wind the tress of hair upon the barrel member 10. In the device shown in Fig. 6 the cap 12 is rotated in a counter

clockwise direction with the same result. As before described, the expanding action of the convolutions 20 and 22 of the devices shown in Figs. 2 and 4, and the expanding action of 5 the arcuate member or members 27 in the device shown in Fig. 6, prevents rotation of the cap 12 and tip 11 in the wrong direction.

Having thus described and explained my invention and its mode of operation, it is to 10 be understood that the apparatus described is selected merely for purposes of illustration and that numerous variations in the form and arrangement of parts shown and described herein may be made without departing from the nature and scope of the invention except as defined in the appended claims.

What I claim is:

1. A hair-curling device comprising a tubular body member, a rotatable tip member mounted at one end thereof, a rotatable cap member mounted at the other end thereof, means connecting said cap and said tip whereby rotation is imparted to said tip by said 20 cap, and means integral with said tubular body for permitting rotation of said cap and tip in one direction only.

2. A hair-curling device comprising a tubular body member, a rotatable tip member 30 mounted at one end thereof, a rotatable cap member mounted at the other end thereof, means connecting said cap and tip whereby rotation is imparted to said tip by said cap, and a thread-like formation integral with 35 said tubular body member and adapted to provide frictional resistance against the rotation of said cap member in one direction.

3. A hair-curling device comprising a tubular body member, a shank extending 40 through said body member, a tip member connected to one end of said shank, a cap member connected to the opposite end of said shank, said cap having a cavity which encases a portion of said tubular body member, 45 said encased portion of the tubular body member having a thread-like formation integral therewith and adapted to engage the cap member to restrict its rotation in one direction.

50 4. A hair-curling device comprising a tubular body member, a shank extending through said body member, a tip member connected to one end of said shank, a cap member connected to the opposite end of said shank, adjustable means associated with 55 said cap and shank for positioning the cap member in various positions on said shank, and positive means incorporated in said cap member for locking the same in any one of its 60 various positions on said shank.

5. A hair-curling device comprising a tubular body member, a shank extending through 65 said body member, a tip member connected to one end of said shank, a cap member connected to the other end of said shank, said

cap member having a cavity into which a portion of said tubular body member extends, and means formed integral with said tubular body member and adapted to provide frictional resistance with the inner surface 70 of said cavity against rotation of said cap member in one direction.

6. A hair-curling device comprising a tubular body member, a shank extending through said body member, a tip member 75 connected to one end of said shank, a cap member connected to the other end of said shank, said cap member having a cavity into which a portion of said tubular body member extends, means formed integral with said tubular body member and adapted to frictionally engage the inner surface of said cavity against rotation of said cap member in one direction, and means associated with 80 said cap and shank for retaining the tip and cap members in fixed relationship to each other.

7. In a hair-curling device, a tubular body member having a spiral groove cut in one end thereof, said groove increasing, in substantially a quarter revolution, to a depth greater than the wall thickness of said tubular body member and proceeding at this increased depth to the end of said tubular body member to constitute a thread-like formation 90 integral with said tubular body member the adjacent convolutions of which are separated, a rotatable tip member mounted at one end of said tubular body member, a rotatable cap member mounted at the opposite end of 95 said tubular body member, said tip and cap members being tied together for simultaneous rotation by means of a shank member extending through said tubular body member, said cap member being provided with a cavity 100 which encases the thread-like formation to provide frictional resistance between said thread-like formation and the interior surface of said cavity thereby permitting rotation of said cap member in one direction only. 110

8. In a hair-curling device, a tubular body member having a thread-like formation integral with one end thereof, said thread-like formation being formed in a manner to provide separated adjacent convolutions, the 115 outside peripheries of which are roughened to produce ridges thereon, a tip member rotatably mounted at one end of said tubular body member, a cap member rotatably mounted at the opposite end of said tubular body member, said cap member being provided with a cavity which encases the thread-like formation, said ridges on the thread-like formation being adapted to cooperate with the interior surface of said cavity to restrain 120 rotation of the cap member in one direction. 125

9. In a hair-curling device, a tubular body member having an arcuate groove cut through the wall of said tubular body member adjacent one end thereof, a slot extend- 130

- ing from the end of said tube to said arcuate groove whereby an arcuate member is provided integrally attached at one end to said tubular body member and separated therefrom at its opposite end, a tip member rotatably mounted at one end of said tubular body member, a cap member rotatably mounted at the opposite end of said tubular body member, said cap member being provided with a cavity which encases the arcuate member, said arcuate member providing frictional resistance on the interior surface of said cavity against rotation of said cap member in one direction.
- 15 10. A hair-curling device comprising a tubular body member, a shank having screw threads formed on its extremities extending through said body member, a tip member and a cap member, said tip and cap members being provided with threaded sockets for attachment to the extremities of said shank member in cooperative relationship with said body member, a cavity in said cap member and means formed integral with said body member adapted to provide frictional resistance with the inner surface of said cavity against rotation of said cap member in one direction, and a set screw disposed in said cap member, said set screw being adapted to be brought into engagement with the end of said shank member whereby the cap and tip members may be secured to the shank in adjustable relationship with respect to said body member.
- 35 30. In testimony whereof I hereto affix my signature.

ROBERT CHESTNUT.
